UNITED STATES PATENT OFFICE.

WILLIAM H. McINTYRE, OF AUBURN, INDIANA.

DESIGN FOR A VEHICLE-SEAT.

No. 39,594.

Specification for Design.

Patented Sept. 29, 1908.

Application filed September 16, 1907. Serial No. 393,232. Term of patent 7 years.

To all whom it may concern:

Be it known that I, WILLIAM H. McINTYRE, a citizen of the United States, residing at Auburn, in the county of Dekalb, in the State of Indiana, have invented a new, original, and ornamental Design for Vehicle- Seats, of which the following is a specification, reference being had to the accompanying drawings, which form part of this specification.

In the drawings Figure 1 is a rear perspective of a vehicle seat, and Fig. 2 is a rear elevation of the same, both views showing my new design.

My invention is provided midway of its ends with a vertical recess to give the seat the appearance of two individual seats.

The upper irregularly curved edge of the seat has an overhanging ornamental bead, as shown, and the lower edge of the seat also has a projecting bead throughout its length.

The seat is divided longitudinally by an outwardly projecting ornamental bead having the same general curvature as that of the seat. The sides and ends of the seat above this last mentioned bead are in vertical arrangement, but the sides and ends of the seat below this bead are oblique or inwardly inclined.

The lower edge of the vertical portion of the seat at the back is separated from the upper edge of the inclined portion by an off set or shelving under cut, as shown in Fig. 1.

I claim:

The ornamental design for a vehicle seat as shown and described.

WILLIAM H. McINTYRE.
